CONRAD SEIMEL, OF BROOKLYN, NEW YORK.

Letters Patent No. 86,038, dated January 19, 1869.

IMPROVEMENT IN SHEET-METAL CANS.

The Schedule referred to in these Letters Patent and making part of the same.

To all whom it may concern:

Be it known that I, CONRAD SEIMEL, of Brooklyn, in the county of Kings, and State of New York, have invented a new and useful Improvement in Sheet-Metal Cans; and I do hereby declare that the following is a full, clear, and exact description of the construction and operation of the same, reference being had to the accompanying drawings, making a part of this specification, in which—

Figures 1, 2, and 3 represent detached sections of my improved joint for sheet-metal cans, and

Figure 4 is a top or plan view of the same.

Similar letters of reference indicate corresponding parts.

This invention relates to an improved method of fastening the tops and bottoms to sheet-metal cans; and

It consists in the peculiar construction of the joint for this purpose, so as to form a rigid, firm, and tight connection, at slight expense, and with but little labor.

In the drawings—

A A represent the sides of a square sheet-metal can, of which B represents the ends or top and bottom.

In forming the joints, where the ends are united to the sides, the latter are first struck or bent up with a flange, *a*, at right angles to the main body *B*.

The top is then formed, as shown in fig. 1, with a right-angular flange, *b*, upon the outside of the depression or gutter *c*.

The ends are applied to the sides by fitting the portion *d* of the former over the flange *a* of the latter. They are then pressed or swaged together by dies, or other suitable means, which will impart to them a curved form without angles, as shown in fig. 2, the part *d* of the top and bottom fitting snugly against the curved under side of the flange *a*.

If desired, a wire, *e*, may be introduced between the flanges *a* *d*, as shown in fig. 3, before these parts are swaged up, in order to impart additional strength to the joint.

With a joint of this construction, solder is not absolutely necessary to render it perfectly tight, as the parts are firmly pressed in contact over a comparatively large surface.

If preferred, however, solder may be employed in small quantities.

It will be observed that these joints extend at right angles to the sides *B* and that they are therefore flattened to form a wide bearing-surface, upon which the cans rest. This is of great advantage in packing oil-cans, as they are thereby enabled to sustain considerable weight without bending the flange, and consequently loosening the joint.

I am aware that sheet-metal cans have heretofore been constructed with diagonal flanges, over which the edges of the tops and bottoms are formed, but this method of construction does not form a safe joint for packing cans of large capacity, from the fact that the weight of the cans and their contents, which in transportation are generally subjected to rough handling, tends to bend the joint outward, or into a horizontal position and thereby loosen it, causing leakage, and a consequent waste of material.

In this construction of cans, the principal means employed for holding the joints, is a thin coating of solder, which a slight blow frequently breaks, opening a wide seam, and rendering the can worthless. My improvement is designed to obviate this difficulty, because, as before stated, the joint forms a wide bearing-surface.

A blow upon this joint cannot have a tendency to open it, from the fact that the slight curve given the parts *a* *b*, directs the joint toward the body of the can, thereby tightening instead of opening it.

When the strengthening-wire is used, the joint is rendered immovable under the roughest handling to which this class of goods is generally subjected.

The simplicity of my improved can, and the economy of its construction, render it a valuable improvement, which will recommend itself to the trade.

Having thus described my invention, what I claim as new, and desire to secure by Letters Patent, is—

The improved method of uniting the tops and bottoms to the sides of square sheet-metal cans, by striking up the same in a slightly curved form, substantially as shown in figs. 2 and 3, for the purpose specified.

The above specification of my invention signed by me, this 16th day of December, 1868.

CONRAD SEIMEL.
